UNITED STATES PATENT OFFICE.

MORTIMOR WOOLF, OF NEW YORK, N. Y.

DESIGN FOR A BOTTLE.

SPECIFICATION forming part of Design No. 16,802, dated July 13, 1886.

Application filed March 18, 1886. Serial No. 195,752. Term of patent 7 years. Registered in England March 5, 1885.
No. 23,184.

To all whom it may concern:

Be it known that I, MORTIMOR WOOLF, a subject of the Queen of Great Britain, residing at New York, in the county and State of New York, have invented and produced a new and original Design for Bottles, of which the following is a specification, reference being had to the accompanying drawing, forming part thereof, which represents a side view of my newly-designed bottle.

The essential feature of my design consists of a curvilinear contraction in the body of the bottle, combined with a flat base, a globular shoulder, and a straight neck with an ornamented piece.

In the drawing, A represents the contracted portion of the bottle, and B the base portion, having rounded outlines b, the bottom B' thereof being of smaller diameter than the body of the base B. The shoulder C is globular, having the center thereof in the line of the axis of the bottle, the outlines of the globular

shoulder C and the base B being connected by the inward curve or curvilinear line E. The neck D is straight and plain, except at its upper part, where it has outer projections, and at the opening or mouth-piece is a bead, as shown in the drawing.

What I claim is—

A design for a bottle, consisting of a base having curved outlines and a bottom of less diameter than the body of the base, a globular shoulder having the center of the axis of the bottle for center of circle of outline, a neck straight and plain, except the upper portion, having outer projections and beaded mouth-piece, all substantially as shown.

Signed at New York, in the county and State of New York, this 24th day of February, 1886.

MORTIMOR WOOLF.
